UNITED STATES PATENT OFFICE.

HORATIO G. CRESS, OF TROY, OHIO, ASSIGNOR TO THE H. G. CRESS COMPANY, OF TROY, OHIO, A CORPORATION OF OHIO.

COMBINED EDUCATIONAL AND GAME BOARD.

Application filed September 8, 1925. Serial No. 54,903.

To all whom it may concern:

Be it known that I, HORATIO G. CRESS, a citizen of the United States, residing at Troy, in the county of Miami and State of Ohio, have invented certain new and useful Improvements in Combined Educational and Game Boards, of which the following is a specification, reference being had thereto in the accompanying drawing.

10 This invention relates to combined educational and game boards and to method of making such boards.

Boards of this character have on one side a smooth uninterrupted surface which may 15 be utilized for a game and on the opposite side a plurality of surfaces in the same general plane with passageways therebetween to receive a set of movable buttons adapted to be positioned in various order therein, the 20 buttons having thereon letters of the alphabet or numerals or any desired matter. The passageways between the several sections comprise what is termed a storage passageway for the general supply of buttons and 25 a transverse or working passageway in which certain buttons are moved, as for spelling a word.

The first branch of my invention consists 30 in the article composed of sections made up of sheets of fiber board laminated or united together to afford thickness and strength and each board before being assembled is cut into the desired shape and size so that the article when finished will be constructed 35 of superimposed layers or thicknesses, each fashioned or cut to perform its function, as will be hereinafter pointed out in detail.

A further feature of the article is the provision, and it is an important one, of a means 40 for draining or discharging from the grooves or passageways in the article that part of the hardening solution, presently referred to, which enters such grooves or passageways and where otherwise it would lodge and prevent completing the article in a proper manner.

The second branch of my invention consists 50 in fabricating the article by means of the following essential steps; first, in cutting or stamping out fiber board of the right shape and size for one outer layer or surface; second, in likewise fashioning several pieces of fiber board of the right shape and size to constitute collectively the other outer 55 layer or surface; third, in likewise fashion-

ing other pieces of fiber board of the right size and shape to constitute the inner thickness or thicknesses; fourth, in assembling the different layers to form a plurality of separate sections and uniting said layers by a suitable adhesive; fifth, in assembling 60 some of said separate sections and applying to the exposed surfaces thereof a hardening solution, as by immersing the sections thus assembled in such hardening solution, for the purpose of stiffening or hardening the fiber board to give it rigidity, durability and more or less finish; sixth, in draining any surplus solution from the assembled units; and, finally, in placing another of 65 the separate sections in position to form a lock to retain a plurality of movable buttons in the board.

In the accompanying drawings:

Fig. 1 is a plan view of my improved 70 board, showing the filler layers in dotted lines;

Fig. 2 is an end elevation looking in the direction of the arrows indicated on the line 2-2 at the right of Fig. 1; 75

Fig. 3 is a sectional view taken on the line 3-3 of Fig. 1;

Fig. 4 comprises a series of views illustrating the buttons used in connection with my improved board; 80

Fig. 5 is a plan view of the base layer;

Fig. 6 shows a series of the filler layer to be secured to the base layer;

Fig. 7 is a plan view of the top layer to be placed above the filler, shown in Fig. 6; 85

Fig. 8 is a plan view of the upper layer of one of the top sections;

Fig. 9 shows a series of the filler layers for the top shown in Fig. 8;

Fig. 10 is a plan view of the top layer of 90 the locking section;

Fig. 11 shows a series of the filler layers for the locking section; and

Fig. 12 is a sectional view of a container for the hardening solution, showing one of 100 the articles suspended therein.

From the drawings it will be seen that my improved board is made up of a plurality of sections which I will term an outer or main section, an inner or supplemental top section and a locking section. These several sections are built up of a plurality of layers of suitable material, preferably fiber board, adhesively secured together.

I will first describe the outer or main sec- 110

tion and the manner in which it is fabricated. In Fig. 5 I have shown a sheet or layer comprising a base proper 1. One face of this layer 1 may be finished in any desired manner, as by applying thereto a sheet containing a game, and the other face has secured thereto a layer fashioned with an opening in the center, as shown in Fig. 6, which constitutes a filler 2. As many of these fillers as desired may be added, but in the present instance, I have employed two. A portion of the abutting faces of each of these fillers is cut away to form an opening 3 extending from the inner to the outer edges thereof, the purpose of which will be hereinafter brought out. In Fig. 7 I have shown another layer 4 fashioned like the fillers shown in Fig. 6 with the exception that the diameter of the opening therein is smaller than the diameter of the opening in the fillers, so that when this layer is secured to the topmost filler 2 a groove will be formed between the base 1 and the layer 4 which forms the top member for the outer section.

The outer section thus fabricated comprises an uninterrupted base 1, an open top 4 with a groove between said parts, and an opening extending from the groove to the outer edge of the section, said outer section forming a sort of container adapted to receive other sections and a plurality of movable buttons.

Referring now to the inner supplemental top section, in Fig. 8 I have shown a layer 5 having the form of a segment of a circle and which comprises the upper member of this section, one face of which may be finished in any desired manner to form the exposed surface constituting a part of the top of the completed article. To the other face I secure one or more fillers 6, fashioned as shown in Fig. 9, the number of fillers in this instance depending upon the number used in making up the outer section, so that when this inner section is placed on the upper face of the base 1 its top surface will be in the same plane as the top 4 of the outer section. The fillers 6 have cut out portions 7 to lighten the completed article. It will also be seen that these fillers are slightly smaller than the portions 5 to leave a space between their outer edges so that a passageway may be formed between the inner and outer sections.

The locking section is made up of the same number of layers as the inner supplemental section, in the present instance, an upper layer 8, fashioned as shown in Fig. 10, and two fillers 9, fashioned as shown in Fig. 11.

After the sections have been thus fabricated the inner supplemental top section and the outer or main section are assembled by

securing the outer filler 6 to the base, leaving a space between the top members 4 and 5 to form a passageway, to accommodate the shank of a movable button 10, such as shown in Fig. 4, the space between the fillers 2 and 6 adapted to receive a head of such button, a plurality of which are used in the use of the device. These sections thus assembled are then immersed in a suitable hardening solution contained in a vessel 11, as shown in Fig. 12.

Upon moving the assembled sections from the solution some of it will remain in the groove formed in the outer section and this would render the board incapable of use as an educational board in which the movable buttons 10 are utilized. Therefore, to remove the solution before it hardens from the groove the opening 3 has been provided, which leads from said groove to the outer edge of the board and permits the surplus solution to drain out. This solution after it dries not only hardens the exposed surface of the sections but imparts to them the appearance of wood.

After the solution has sufficiently hardened a plurality of the buttons 10 are placed in the passageway 12 formed between the inner and outer sections. The locking section is then inserted and its filler 9 secured to the base of the outer section. This locking section not only serves to hold the buttons in the board but also cooperates with the straight edge of the inner supplemental section to form a working passageway 13 communicating at either end with the general or storage passageway 12, which is continued around the curved edge of the locking section. In the use of the device, as when it is desired to spell a word, the buttons having the desired letters are moved from the storage passageway 12 to the working passageway 13 in the proper order.

The passageways for the heads of the buttons must be larger than the passageways for the shanks. That part of the storage passageway for the heads is formed by the inner periphery 2^a of the fillers 2 and the outer curved edges 6^a and 9^a of the fillers 6 and 9, respectively, while that part of the transverse or working passageway for the heads is formed by the straight edges 6^b of the fillers 6 and the straight edges 9^b of the fillers 9.

That part of the storage passageway for the shanks of the buttons is formed by the inner periphery 4^a of the top 4 and the outer curved edges 5^a and 8^a of the fillers 5 and 8, respectively, while that part of the transverse or working passageway for the heads is formed by the straight edges 5^b of the top 5 and the straight edge 8^b of the top 8 of the locking section.

It will be seen that my method consists;

in cutting or stamping fiber board of the desired shape and size for fabricating an outer or main section which forms the general base of the completed article and a 5 sort of container for the other sections comprised in the article and also in providing an opening in said section extending from the outer edge to the inner edge; in likewise cutting or stamping fiber board of the desired shape and size for fabricating the 10 inner section which forms a part of the top of the completed article and cooperates with the outer section to form a passageway for a plurality of movable buttons; in likewise cutting or stamping fiber board of the desired shape and size for fabricating the locking section which cooperates with the outer and inner sections to form additional passageways and retains the buttons in said 15 passageways; in assembling the outer and inner sections and immersing them in a hardening solution; in draining any surplus hardening solution from said assembled sections; and in uniting the locking section 20 with the sections thus assembled, after the desired number of buttons have been inserted.

It will thus be seen that I have provided a combined educational and game board 30 which may be made up of a plurality of sheets or layers which will have all the advantages of such boards made of wood as to appearance and durability and none of the disadvantages of wood, such as warping, 35 etc. It will further be observed that the board thus built up will be light in weight and inexpensive to produce.

It will be understood that I desire to comprehend within my invention such modifications as may be necessary to adapt it to varying conditions and uses.

Having thus fully described my invention, what I claim as new and desire to secure by Letters Patent, is:—

45 1. In an article of the character described, a plurality of sections, each of said sections composed of superimposed fashioned layers or thicknesses, said sections having spaces therebetween to form communicating passageways for a plurality of buttons, and one of said sections having an opening extending from said passageways to the outer edge of said section.

55 2. In an article of the character described, an outer section, an inner section and a locking section, each of said sections composed of superimposed fashioned layers or thicknesses, said sections having spaces therebetween to form communicating passageways for a plurality of buttons, said outer section having an opening communicating with said passageways and leading to the outer edge of said section to form

a drain for a hardening solution in which the sections are immersed.

3. The herein described method of making a combined educational and game board consisting of fashioning a plurality of outer members and a plurality of intermediate members; uniting these outer and intermediate members into a plurality of sections; assembling some of said united sections so as to form a passageway therebetween, immersing said assembled sections in a hardening solution; and draining surplus solution from said assembled sections.

4. The herein described method of making a combined educational and game board consisting of fashioning a plurality of outer 80 members and a plurality of intermediate members; uniting these outer and intermediate members into a plurality of sections; assembling some of said united sections so as to form a passageway therebetween, immersing said assembled sections in a hardening solution; draining surplus solution from said assembled sections, and positioning another of said united sections with respect to the assembled sections to lock a plurality 85 of buttons in the passageways formed between the several united sections.

5. The herein described method of making a combined educational and game board consisting of fashioning a plurality of outer 95 members and a plurality of intermediate members; uniting these outer and intermediate members into a plurality of sections; providing an opening in one of said sections extending from its outer edge to 100 its inner edge; assembling this section with another united section so as to form a passageway therebetween; immersing said assembled sections in a hardening solution; and draining the solution from said passageway through said opening.

6. The herein described method of making a combined educational and game board consisting of fashioning a plurality of outer 110 members and a plurality of intermediate members; uniting these outer and intermediate members into a plurality of sections; providing an opening in one of said sections extending from its outer edge to 115 its inner edge; assembling this section with another united section so as to form a passageway therebetween; immersing said assembled sections in a hardening solution; draining the solution from said passageway through said opening; and positioning 120 another of said united sections with respect to the treated assembled sections to lock a plurality of buttons in the passageways formed between the several sections.

In testimony whereof, I affix my signature
HORATIO G. CRESS
